UNITED STATES PATENT OFFICE.

WILLIAM T. ARNOLD, OF CHICAGO, ILLINOIS, ASSIGNOR TO THE CHICAGO ELECTRIC PROTECTIVE COMPANY, OF SAME PLACE.

BURGLAR-ALARM SYSTEM.

SPECIFICATION forming part of Letters Patent No. 587,669, dated August 3, 1897.

Application filed December 15, 1896. Serial No. 615,816. (No model.)

To all whom it may concern:

Be it known that I, WILLIAM T. ARNOLD, a citizen of the United States, residing at Chicago, in the county of Cook and State of Illinois, have invented a certain new and useful Improvement in Burglar-Alarm Systems, (Case No. 6,) of which the following is a full, clear, concise, and exact description, reference being had to the accompanying drawings, forming a part of this specification.

My invention relates to burglar-alarm systems, and has for its objects the provision of improved means for automatically testing the condition of the protecting-circuits associated with guarded structures, and improved means at the central office for indicating abnormal changes in said protected circuits.

In a patent to Alfred Stromberg, No. 477,712, issued June 28, 1892, is shown and described a burglar-alarm system in which a resistance is included in series between two sets of protecting-conductors. A battery and signal apparatus at the central office is normally included in circuit with the said protecting-conductors, the aforesaid resistance serving to reduce the battery-current sufficiently to prevent the operation of the signal apparatus. A clockwork device is employed in this system, one being located at each protected station, which is adapted to shunt this resistance at regular intervals, whereby the aforesaid signal apparatus is caused to operate. Each clockwork mechanism is under the control of the subscriber at the station where it is located.

One feature of my invention consists of devices for short-circuiting the aforesaid resistances, one located at each subscriber's station, under control of apparatus at the central office, whereby accuracy of tests is assured.

Generally speaking, the preferred form of one feature of my improved burglar-alarm system comprises a round circuit including a relay at each subscriber's station, a resistance and main battery at the central office, and clockwork mechanism adapted to shunt said resistance at regular intervals, whereby the battery-current through the said relays is increased sufficiently to cause the attraction of the armatures thereof. The armatures of the

relays at the different subscribers' stations are thus simultaneously attracted, and upon being attracted shunt the artificial resistance between the protecting-conductors, whereby signal apparatus at the central office is operated.

What I term "governor-relays" are located at the central office, one being included in circuit with the protecting-conductors at each subscriber's station and the aforesaid main battery. When the resistance at the subscriber's station is shunted, as aforesaid, these governor-relays serve to operate visual signals. These governor-relays also serve to operate another set of signals, preferably both audible and visual, when any of the conductors become broken.

My invention will be more readily understood by reference to the accompanying drawings, in which—

Figure 1 is a diagrammatic view of a burglar-alarm system embodying my invention. Fig. 2 is a view in elevation of a governor-relay that I prefer to employ in practicing my invention. Fig. 3 is a sectional view on line 3 3 of Fig. 2. Fig. 4 is a view in elevation of a visual signal which I prefer to employ, this signal being actuated upon the shunting of the artificial resistance of the corresponding subscriber's station.

Like letters and figures refer to like parts throughout the different views.

Three subscribers' stations 1, 2, and 3 are shown. Conductor a extends from the central office A to the station 1 and includes in circuit therewith at said station a protecting-conductor a' , which is included in circuit with the protecting-conductor a^2 either through the artificial resistance a^3 or a shunt adapted to be completed about said resistance by the armature a^4 and contact a^5 . The common return b completes the circuit of the protecting-conductor at the subscriber's station back to the central office. Subscribers' stations 2 and 3 are each similarly provided with protecting-conductors a' a^2 , artificial resistance a^3 , armature a^4 , and contact a^5 .

The protecting-conductor a' at station 2 is in circuit with a line c , extending from the subscriber's station to the central office, the circuit being completed through conductor a^2 .

and the common return b . The protecting-conductor a' at subscriber's station 3 is included in circuit with a line d , extending from the subscriber's station to the central office, this circuit being completed by way of protecting-conductor a^2 and the common return b .

Governor-relays e , f , and g are included in circuit with the lines a , c , and d , respectively, the common return b , conductor b' , and main battery h serving to complete the circuits through the governor-relays, which are thus normally energized. The governor-relays are preferably constructed as shown in Figs. 2 and 3, in which two magnets e' e' are axially alined. Between the opposing poles of the magnets is provided an armature e^2 , pivoted at e^3 , this armature being preferably polarized and presenting, for example, a polarity of positive sign to the opposed poles of the electromagnets. Magnet e' upon the left is wound to present a polarity of negative sign to the armature, while the magnet upon the right is wound to present a polarity of positive sign. The tendency of the armature, therefore, is to rotate in a contra-clockwise direction about its pivot.

In order to maintain the armature normally in a central position, which is desired in connection with the present system, I provide an adjustable rider e^4 , supported upon and located beneath the pivot or armature, and which is adapted to counteract the repelling and attractive forces exerted upon the armature by the electromagnets. If any of the conductors in circuit with the governor-relay should become broken, the magnets will be de-energized and the armature rotated upon its pivot by the rider e^4 in a clockwise direction, the armature being brought into contact with the adjustable contact-anvil e^5 . When the artificial resistance included in circuit with the governor-relay is shunted, the magnets will be increased in strength, whereby the attractive and repelling forces upon the armature are increased and the armature rotated in a contra-clockwise direction, causing contact between the armature and the adjustable contact-anvil e^5 . A light spring e^6 is impinged upon by the armature when it is swung to this position, this spring being thereby thrown into contact with the anvil e^5 , for the purpose hereinafter set forth.

I preferably provide permanent magnets e^9 e^9 , which serve to quickly return the armature to its central position, when the magnets e' e' are energized to their normal strength.

Parts of the governor-relays e , f , and g , similar to the parts shown in Figs. 2 and 3, are given similar letters of reference.

Visual signals i , k , and l are provided, which are under the control of the relays e , f , and g , respectively. These signals are operated by the armatures of the governor-relays when they are swung in a contra-clockwise direction, this movement of the armature being effected, as aforesaid, when the resistance at

the subscribers' stations is removed from circuit with the battery h and the governor-relays. The manner in which the artificial resistances at the subscribers' stations are short-circuited will be set forth hereinafter.

The visual signals are preferably constructed as shown more clearly in Fig. 4, in which two axially - alined magnets k' k' are provided, between which is centrally disposed an armature k^2 , pivoted at k^3 . A screen k^4 is provided with an aperture before which the target, carried upon the end of the armature and bearing the visual signal, is normally disposed. The armature is preferably polarized, presenting, for example, a polarity of positive sign to the opposed poles of the magnet, the contiguous pole of the magnet upon the left being adapted to present a positive pole to the armature while the magnet upon the right presents a negative pole when said magnets are energized.

The rider k^5 is provided to normally keep the armature in the angular position shown. When the magnets are energized, the armature is thrown into the central position shown by dotted lines, a detent k^6 , in the nature of a light spring carried upon a rod k^7 , engaging said armature to prevent its return to its angular position.

The parts of visual signals i , k , and l , similar to the parts shown in Fig. 4, are given similar letters of reference.

Visual signals m , n , and o are controlled by the governor-relays e , f , and g , respectively, while the audible signal p is controlled by each of the governor-relays. These signals m , n , o , and p are adapted to be operated by any of the governor-relays when de-energized—as, for example, if a conductor in circuit with governor-relay e is broken signals m and p will be included in circuit with battery q , conductor q' , armature e^2 of relay e , contact-anvil e^5 of said relay, conductor q^2 , switch q^3 , conductors q^4 and q^5 , the signal m will appear, and the signal p will sound.

A round circuit r is provided which includes a relay-magnet a^6 at each subscriber's station, relay r' at the central office, battery h , resistance r^2 , and relay r^3 . The resistance r^2 is high enough to reduce the current of battery h sufficiently to prevent the attraction of armatures a^4 a^4 a^4 by the magnets a^6 a^6 a^6 .

A shunt is provided about the resistance r^2 , comprising the conductors s s' , spring s^2 , and a wheel s^3 , driven preferably by a clock-train. This wheel is provided with teeth, one of which is adapted to engage the spring s^2 at regular intervals, say once a minute, thereby completing the shunt about the resistance r^2 .

The short-circuiting relays at subscribers' stations, each of which comprises the magnet a^6 , armature a^4 , and anvil a^5 , are thus simultaneously operated to shunt the artificial resistance at each subscriber's station, whereby the armatures of the governor-relays are simultaneously brought into contact with the anvils a^5 , the engagement between the arma-

tures and the contact-anvils e^6 serving to operate the signals i , k , and l , whose targets are removed from the openings in the screen k^4 . At the same time the terminals e^7 and e^8 of each governor-relay are simultaneously brought into contact, these terminals serving to close a normally open shunt-circuit about the audible signal t . This shunt includes the aforesaid terminals, conductor t' , battery q , conductor q' , thence through any of the armatures of the signals e , f , and g , connected with conductor q' , and any of the conductors, including the signals i , k , and l , the shunt-circuit being completed by conductor t^2 , which includes the terminals e^7 and e^8 .

If for any reason the short-circuiting relays at the subscribers' stations should fail to cut out the artificial resistances a^3 , the corresponding governor-relay will fail to operate. For instance, if the short-circuiting relay at subscriber's station 1 should fail to cut out the artificial resistance a^3 the relay e will fail to operate and the armature thereof will remain in its central position. The shunt-circuit about the bell t will be opened at the terminals e^7 and e^8 , controlled by relay e , the battery q being thereby included directly in circuit with signal t , which will sound and attract the operator's attention. The target of signal i , together with its supporting-armature, will remain in the position shown. The operator hearing the signal t then notices the visual signals and knows by the condition of signal i that the trouble is located at subscriber's station 1.

The rod k^7 , supporting the springs k^6 , is attached to the armature of the electromagnet u , which is adapted to be included in a local circuit with the battery u' , spring u^2 , and wheel s^3 . The spring u^2 is adapted to make contact with a tooth of the wheel s^3 shortly after the engagement of the spring s^2 with one of said teeth, whereby the armature of magnet u is attracted and the rod k^7 partially rotated upon its pivot k^8 , the springs k^6 being thus removed from engagement with the armatures k^2 , which are caused to resume their angular positions by the weight k^5 , the visual signals being thereby restored shortly after they are operated in consequence of the short-circuiting of resistance r^2 . Thus the artificial resistances at the subscriber's station are periodically and simultaneously cut out of circuit, thereby causing the simultaneous appearance of the targets of the signals i , k , and l , these operations taking place without the slightest attention from the operator unless any of the governor-magnets should fail in its work, when the audible signal t will be caused to respond to attract the operator's attention. Heretofore a large amount of apparatus had to be constantly under the watchful care of the operator, which I am thus enabled to dispense with.

It will be understood that the conductors a , b , c , and d , extending to the subscribers' stations, are all led into the guarded struc-

ture at one point. Now if the burglar in entering should accidentally connect the conductors a , b , c , or d the corresponding resistance a^3 will be shunted and the signal t and the corresponding visual signal operated.

In practice I extend each round circuit through twenty-five subscribers' stations, each circuit having associated therewith a bank of twenty-five governor-relays and fifty visual signals, twenty-five of which, similar to signals i , k , and l , are adapted to indicate the short-circuiting of the artificial resistance at the subscribers' stations, while the other twenty-five signals, similar to m , n , and o , are adapted to indicate the opening of lines extending to the subscribers' stations. Each round circuit is separate and distinct from the others. If either of the conductors a , b , c , or d should become connected with conductor r , the magnet r^3 , which is of high resistance, will become short-circuited, and the signal v included in a local circuit with battery v' by the armature of said magnet when released.

I ground the conductor r preferably at w . If the conductor r should be grounded at any other point, as in the act of effecting an entry into the guarded structure, the magnet r' would be short-circuited and signal w' included in a local circuit with battery w^2 by the armature of said magnet.

If the conductor r should be opened at any point, both the magnets r' and r^3 would be deenergized, whereby the signals v and w' will both be operated. I include an electromagnet x in the common return b , which is normally energized by the battery h . If the common return should be opened, or if a ground should be put upon the same, the armature of electromagnet x will close a local circuit through the signal y and the battery w^2 , causing said signal to give an alarm.

It is clear that the details of the system of my invention may be somewhat modified without departing from the principles involved.

I have purposely omitted the description of minor details and the enumeration of many modifications which may be made without departing from the principles of my invention, because to set these forth at length would obscure rather than make clear the more essential features.

In the claims I speak of removing resistance in the sense of short-circuiting or otherwise completing a path of low resistance about the same.

Having, however, fully set forth one manner of practicing my invention, I claim, and desire to secure by these Letters Patent, together with all such modifications as may be made by mere skill and with only the limitations expressed or by law implied, the following:

1. In a burglar-alarm system, the combination of a subscriber's station having protecting conductors or apparatus connected with

the central office, with a resistance at the subscriber's station in circuit with said conductors or apparatus, a relay at the subscriber's station for removing said resistance, 5 a source of electricity and a resistance at the central office in circuit with said relay, automatic means at the central office for removing said resistance periodically, and suitable indicating apparatus at the central office 10 adapted to respond to a change in the circuit condition at the subscriber's station, substantially as described.

2. In a burglar-alarm system, the combination of a plurality of subscribers' stations each 15 having protecting conductors or apparatus connected with the central office, with a resistance at each subscriber's station in circuit with said conductor or apparatus, a relay at each subscriber's station for removing said resistance, a round circuit extending from the central office to the subscribers' stations in which said relays are included, means at the central office connected with said round circuit for operating said relays, and suitable 20 indicating apparatus at the central office adapted to respond to a change in the circuit conditions at the subscribers' stations, substantially as described.

3. In a burglar-alarm system, the combination of a plurality of subscribers' stations each 30 having protecting conductors or apparatus connected with the central office, with a resistance at each subscriber's station in circuit with said conductors or apparatus, a relay at each subscriber's station for removing said resistance from circuit with said conductors or apparatus, a round circuit extending from the central office to the subscribers' stations and including said relays, a resistance and a 35 source of electricity included in said round circuit, means at the central office for removing the latter resistance from the round circuit, and suitable indicating apparatus at the central office adapted to respond upon a 40 change in the circuit conditions at the subscribers' stations, substantially as described.

4. In a burglar-alarm system, the combination of a plurality of subscribers' stations each 45 having protecting conductors or apparatus connected with the central office, with a resistance at each subscriber's station, in circuit with said conductors or apparatus, a relay at each subscriber's station for removing said resistance from circuit with said conductors or 50 apparatus, a round circuit extending from the central office to the subscribers' stations and including said relays, automatic means connected with said round circuit adapted to periodically remove the latter resistances at the 55 subscriber's station from circuit with said conductors or apparatus, and suitable indicating apparatus adapted to respond to a change in the circuit condition at the subscriber's station, substantially as described.

5. In a burglar-alarm system, the combination of a plurality of subscribers' stations each 60 having protecting conductors or apparatus

connected with the central office, with a resistance at each subscriber's station in circuit with said conductors or apparatus, a relay at 65 each subscriber's station for removing said resistance from circuit with said conductors or apparatus, a round circuit extending from the central office to the subscribers' stations and including said relays, a resistance and a source 70 of electricity at the central office included in said round circuit, automatic means for periodically removing the latter resistance, and suitable indicating apparatus adapted to respond to a change in the circuit condition at 75 the subscriber's station, substantially as described.

6. In a burglar-alarm system, the combination of a plurality of subscribers' stations with protecting conductors or apparatus at 80 each subscriber's station connected with the central office, governor-relays at the central office, one corresponding to each subscriber, adapted to respond upon a change in the condition of the circuit at the subscribers' stations, means for simultaneously changing the circuit condition at the subscribers' stations whereby said governor-relays are simultaneously operated, an audible signal adapted to be operated by one of said relays, and means 85 jointly controlled by said governor-relays for preventing the operation of said audible signal, substantially as described.

7. In a burglar-alarm system, the combination of a plurality of subscribers' stations, 90 with protecting conductors or apparatus at each subscriber's station connected with the central office, governor-relays at the central office, one corresponding to each subscriber adapted to respond upon a change in the condition of the circuit at the subscribers' stations, means for simultaneously changing the circuit condition at the subscribers' stations whereby said governor-relays are simultaneously operated, and a signal jointly controlled by said relays, substantially as described.

8. In a burglar-alarm system, the combination of a plurality of subscribers' stations with protecting conductors or apparatus at 115 each subscriber's station connected with the central office, governor-relays at the central office, one corresponding to each subscriber adapted to respond upon a change in the condition of the circuits at the subscribers' stations, means for simultaneously changing the circuit conditions at the subscribers' stations whereby said governor-relays are simultaneously operated, an audible signal adapted to be operated by one of said 120 relays, means jointly controlled by said governor-relays for preventing the operation of said signal, and visual signals, one associated with and controlled by each governor-relay, substantially as described.

9. In a burglar-alarm system, the combination of a plurality of subscribers' stations each having protecting conductors or apparatus, governor-relays, one connected with

each subscriber's station, adapted to be operated upon a change in the circuit condition at the subscribers' stations, an audible signal adapted to be operated by one of said governor-relays, said governor-relays being jointly adapted when simultaneously actuated to prevent the operation of said audible signal, means for simultaneously changing the condition at the subscribers' stations, and visual signals operated by said governor-relays, one visual signal being associated with and controlled by each governor-relay, substantially as described.

10. In a burglar-alarm system, the combination of a plurality of subscribers' stations each having protecting conductors or apparatus connected with the central office, governor-relays, one in circuit with the apparatus at each subscriber's station, an audible signal adapted to be operated by one of said governor-relays, said governor-relays when actuated simultaneously being adapted to prevent the operation of said audible signal, visual signals, one controlled by each governor-relay, a resistance at each subscriber's station in circuit with said protecting conductors or apparatus, a relay at each subscriber's station for removing said resistance, a round circuit including said relays and extending to the central office, and automatic means at the central office connected with said round circuit adapted to periodically and simultaneously operate the relays at the subscribers' stations, substantially as described.

15. 11. In a burglar-alarm system, the combination of a plurality of subscribers' stations each having protecting conductors or apparatus connected with the central office, governor-relays, one in circuit with the apparatus at each subscriber's station, an audible signal adapted to be operated by one of said governor-relays, said governor-relays when actuated simultaneously being adapted to prevent the operation of said audible signal, visual signals, one controlled by each governor-relay, a resistance at each subscriber's station in circuit with said protecting conductors or appa-

ratus, a relay at each subscriber's station for removing said resistance, a round circuit including said relay and extending to the central office, a resistance and a source of electricity included in said round circuit, an automatic means for periodically removing said resistance from said round circuit, substantially as described.

55

12. In a burglar-alarm system, the combination of a plurality of subscribers' stations each having protecting conductors or apparatus connected with the central office, signals as *i*, *h* adapted to be actuated upon a change in the circuit condition at the subscribers' stations, each of said signals having a movable element as *k*² which presents the signal, a rod *k*⁷ having springs or detents *k*⁶ supported thereon, said detents being adapted to engage said movable elements, an electromagnet *u* adapted to operate said rod *k*⁷ to permit of the restoration of said signals, means for simultaneously changing the circuit condition at the subscribers' stations, and means for operating said electromagnet, substantially as described.

60

13. In a test system for burglar-alarm apparatus, the combination with a plurality of subscribers' stations, each having protecting apparatus, means for simultaneously changing the circuit conditions of the protecting apparatus at all of the subscribers' stations, and a signal device at the central office jointly controlled by the protecting apparatus at all of the subscribers' stations and adapted, upon the failure of said means to change the circuit condition of the apparatus at any subscriber's station, to give a signal through the agency of the protecting apparatus at the remaining stations whose conditions are changed, substantially as described.

70

In witness whereof I hereunto subscribe my name this 10th day of December, A. D. 1896.

WILLIAM T. ARNOLD.
